WIRE STRIPING DEVICE

Karl H. Weber, Toledo, Ohio

Application February 7, 1955, Serial No. 486,340

8 Claims. (Cl. 118—221)

This invention relates to a striping device for electrical conductors, which incorporates a means for supplying ink to the striping mechanism to allow substantially continuous operation of the device.

Devices for placing a distinctive ink stripe or stripes on the outer surface of insulated conductors or the like, such as disclosed by Hargreaves et al. Patent No. 2,344,610, have the disadvantage that the ink supply available during operation of the device is limited with the result that the device is not suitable for use in continuous production. The machine must be stopped after a short period of operation for the purpose of replenishing the ink supply which makes the machine limited in its application to modern manufacturing processes.

The present invention contemplates the provision of a means for replenishing and supplying ink to the striping device which can be controlled, so that no stoppage of the striping machine is necessary and continuous operation thereof becomes feasible.

The invention further contemplates the provision of an ink supply means for a striping machine which continuously circulates the ink and which is provided with a controlled supply to replenish ink to the system as it is being used, and also to maintain a controlled supply of ink in the system.

It is, therefore, a principal object of this invention to provide an ink-striping device for insulated conductors or the like which is capable of substantially continuous operation.

It is a further object of this invention to provide an ink-supplying means for a wire-striping machine which circulates the ink continuously, maintains the ink at a predetermined level to control the quantity of ink in the machine, and adds ink to the system to replenish the supply as it is being used by the machine.

Other objects and advantages of this invention relating to the arrangement, operation and function of the related elements of the structure, to various details of construction, to combinations of parts and to economies of manufacture, will be apparent to those skilled in the art upon consideration of the following description and appended claims, reference being had to the accompanying drawings forming a part of this specification wherein like reference characters designate corresponding parts in the several views.

Referring to the drawings:

Fig. 1 is an elevational view of a complete machine incorporating the invention;

Fig. 2 is a plan view, with its cover removed, of the striping unit;

Fig. 3 is a sectional elevation with some parts removed of the striping unit;

Fig. 3A is a view of a conductor or strand striped by the machine;

Fig. 4 is an elevational view, partly in section, taken partially along line 4—4 of Fig. 2 having one rotatable inking unit shown as in Fig. 3 aligned therewith;

Fig. 5 is an elevational view, in section, taken par-

tially along line 5—5 of Fig. 2 with the elements of the second inking unit in alignment;

Fig. 6 is an elevational view, in section, taken partially along line 6—6 of Fig. 2 with the third inking unit in alignment;

Fig. 7 is a plan view of one of the inking units;

Fig. 8 is an elevational view taken along line 8—8 of Fig. 7;

Fig. 9 is an elevational view, partly in section, taken along line 9—9 of Fig. 2 showing the details of an ink supply reservoir; and

Figs. 10 to 12 are elevational views of details of construction.

Referring to the drawings, particularly to Fig. 1, a striping machine is shown to which the invention has been applied, comprising a base member 20, mounted on legs 22, adjacent a supply reel 24 rotatably held in a fixed member 26, the reel being filled with insulated wire to which the identifying stripe is to be applied. The end 15 of the continuous strand S of insulated wire is lead into the striping device through a wire tension unit T, thence through a drive mechanism D into the striping unit U, thence through a dryer X, and into a second tension unit T' and finally into the take-up spool or drum Y, which 20 is suitably driven by an electric motor M so as to pull the strand S through the various stations of the machine from the supply spool or reel 24. The drive unit D is 25 actuated by the pull on the strand in a manner to rotate the striping mechanism as will be described hereinafter.

30 A small portion of the strand S is shown in Fig. 3A, where the stripes are shown in relation to the strand's outer surface. The spirals are preferably three in number, spaced at selected intervals, preferably uniformly spaced and given contrasting colors and varying widths, 35 so that the strand may be instantly recognized by these markings to facilitate making intricate connections between various instrumentalities at widely separated locations.

The tension devices T and T' located on opposite sides 40 of the striping unit are well known in the art and may take many forms and will, therefore, not be described in detail. These units are intended to maintain a substantially uniform tension on the strand S as it passes through the striping unit, and may consist of several 45 sheaves, about which the strand S passes, one of which is provided with a drag member or brake as is well known.

The strand S of insulated wire, after passing through the first tension device T, enters the driving unit D by 50 passing around sheave 30, which is suitably journaled about a fixed pintle mounted in the side of the base 20, the pintle also rotatably mounting arm 32 on whose outer end roller 34 is mounted to contact the periphery of a second double sheave 36, around which the strand S is threaded. The double sheave 36 has two peripheral 55 grooves, both of which are engaged by the strand S, the first receiving the strand as it comes from the sheave 30, while the second groove is engaged by the strand as it comes from a third sheave 38 rotatably mounted in space relation to the double sheave 36. The double sheave 36 and the next single sheave 38 are geared together by a central idler gear 40. The two sheaves with their cooperating gear are rotatably mounted in fixed 60 spaced relation on fixed journals mounted on the base 20 as shown in Fig. 1. From the second groove in the sheave 36, the strand S proceeds upwardly into the bore of a central rotating shaft 42 of the striping unit (Fig. 3) which is rotated by a gear chain consisting of bevel gears 44 and 46, and spur gears 48 and 50, which transmit rotative motion from the double sheave or gear 36 65 to the hollow central shaft 42 at a predetermined ratio, so that the shaft 42 will rotate a predetermined number of revolutions per foot of the strand S passing through

the grooves of the sheaves 36 and 38. Inasmuch as the strand S is pulled through the device by the motor M, as already described, the friction between the strand and the sheaves 36 and 38 will create a driving relation to rotate the shaft 42 at the predetermined speed. The first bevel gear 44 is affixed to the double sheave 36, to drive the idler gears 46 and 48 affixed together and suitably journaled in the base to drive spur gear 50 affixed to the lower end of shaft 42.

The hollow shaft 42 is vertically journaled in ball bearings 52 and 54, mounted on the interior of a protective tube 56 by collars 58 and 60 suitably affixed to the tube which, in turn, is attached to the upper side of the base member 20. The collar 60 is provided with an outwardly-extending flange 62 overhanging the top end of tube 56 (Fig. 3), on the upper side of which a plate-like ink-retaining member 64 is affixed, pierced by a central aperture mounting a bearing sleeve 66, in which is journaled a depending hollow central stem 68, affixed at its lower end in a central recess 69 of the shaft 42, by set screws 70, and provided at its upper end with a horizontal integral turn table 72, to be further described hereinafter. The upper side of the member 64 is provided with a shallow concentric recess 74 in which the turn table 72 is rotatable, so that its upper surface is flush with the upper surface of the member 64. The floor of the recess 74 is provided with annular ink-retaining pockets 76, 78 and 80 concentric with the axis of rotation of the shaft 42 and the turn table 72. Beyond the locus of the recess 74, the upper surface of the member 64 is pierced with a second set of annular pockets 82, 84, and 86, which are also concentric with the aforementioned axis of rotation of the shaft 42, therefore, are also concentric with the ink-retaining pockets 76, 78, and 80. The second set of annular pockets are of varying depths, as is clearly shown, and bores are provided to interconnect the pockets as follows: referring to Fig. 4, it will be noted that pocket 80 is connected to outer pocket 86 by a pair of vertical bores 88 and 90 which connect with horizontal bore 92; referring to Fig. 5, pocket 78 is connected with outer pocket 84 by a pair of vertical bores 94 and 96 which connect with horizontal bore 98, and referring to Fig. 6, pocket 76 which is outermost of the ink-retaining pockets is connected with the outer pocket 82 by vertical bores 100 and 102, which connect with horizontal bore 104. The purpose for this will appear hereinafter.

Horizontal bores 92, 98 and 104 are bored from the perimeter of the member 64, as is best seen in Figs. 4, 5 and 6, with the open outer end of the bores being fitted with pipes 106, 108 and 110 threaded into the respective bores. Each of the outer ends of the pipes is provided with a sump 112, provided with a petcock 114 for drainage and an overflow pipe 116 to predetermine the maximum level of ink or dye in the various pockets. The construction of each of these elements with reference to the various pockets is substantially the same and serves the same purpose for each pocket.

Referring now to Figs. 2 and 9, the ink or dye-replenishing system will be described. Cylindrical storage chambers 118, 120 and 122 are provided, one for each ink pocket, which are attached to the perimeter of the member 64 in any convenient manner as by blocks 124, 126 and 128, into which pipe and valve assemblies 130, 132 and 134 are positioned on the lower side of each cylinder by threads as shown. Each valve assembly is preferably provided with a sight window 136, through which the amount of flow of dye or ink may be observed, so that the valve may be controlled by its manual control knob 139 to suit the requirements of the striping mechanism during continuous use. This may be determined by observing the level of ink or dye in each pocket in the cooperating sumps 112, with superfluous ink flowing off through the overflow pipes 116, so that the valves from the supply chambers can conveniently be adjusted to supply the proper amount of ink to the machine as needed.

The assemblies 132 are in communication with the outer annular pockets 82, 84 and 86 as shown in phantom in Fig. 2 by pipes 137, 138, and 140 with a cross-sectional view shown in Fig. 9, illustrating the connection of the central outer pocket 84 by means of pipe 138. To illustrate the flow of ink from the supply chamber 120 to the center inner ink pocket 78, it first drips past the sight window 136, into the pipe assembly 132, thence by pipe 138 to the outer center pocket 84, and finally through vertical bore 96 to the horizontal bore 98 (Fig. 5) to vertical bore 94 to the inner ink pocket 78. The ink will assume its own level via pipe 108 to the sump 112 as already described to give indication of the supply of ink available in the system. The same flow pattern of the ink applies to the other two ink systems in the same way.

It will be observed that the strand S passes upwardly through the central bore 150 of the hollow shaft 42, thence through the central bore 152 of the stem 68 of the turn table 72 affixed in the counterbore 69 of the shaft 42 into an upstanding guide tube 154 extending upwardly from the flat horizontal upper surface of the turn table. The guide tube 154 is preferably press-fitted into an enlargement 156 of the bore 152. Adjacent the upper end of the guide tube 154 the strand S engages the periphery of three marking discs (Fig. 2) 158, 160, and 162, mounted obliquely on the upper surface of the turn table so as to be on the skew with reference to the axis of the wire whereby a spiral marking will be provided on the surface of the strand as it moves through the zone in the locus of the marking wheels or discs. As has already been described, the strand is pulled through this zone and by the strand actuating the driving mechanism D, the turn table 72 is rotated about the strand, on which are rotatably mounted the marking discs, which, by their peripheral contact with the surface of the strand S, are rotated thereby. The marking discs or wheels are described and claimed in Patent No. 2,344,610 to Hargreaves et al.

The spacing of the marking wheels or discs about the perimeter of the turn table controls the spacing of the stripes on the surface of the strand S, and may, therefore, vary widely to suit prescribed conditions. The wheels, as shown in Fig. 2, are not symmetrically arranged about the strand S, so that a state of physical imbalance arises and, therefore, requires a balancing weight 164 to be attached to the turn table. This is essential to reduce vibration at the relative high speed of rotation at which the turn table 72 rotates about the strand S.

Each of the marking wheels 158, 160, and 162 is mounted on a journal shaft 166 by a suitable bearing, so that it may be rotated with ease by its peripheral contact with the strand S. The journal shaft 166 is affixed in the sides of a bifurcated holder 168, which is, in turn, mounted in a housing 169, so that the wheel is rotatably held at a suitable angle on the skew with reference to the strand S, and in a position to project from the open front face of the cup-shaped housing 169, as is best seen in Figs. 3 and 8, where contact is made with the strand. The cup-shaped housing is obliquely mounted at the same angle of skew as the wheel in radial juxtaposition on the turn table 72 by screws 170 fitted through suitable apertures in ears 172 at the base of the housing (Fig. 8). The holders 168 are made adjustable by being mounted on pintles 174 positioned in an upward projection 176 of the housing 169, the adjustment control being provided by a rearwardly-projecting arm 178 cooperating with a set screw 180 positioned in locked threaded relation at the upper end of the housing. The arm 178 is spring biased against the set screw 180, by an adjustable spring-urged plunger 182 positioned on the upper side of the projection 176, being preferably made adjustable to control the spring bias in any well known manner.

The housings 169 form closed pockets 183 about the rear sides of the marking discs or wheels and catch excess ink or dye which may be thrown outwardly from the

wheels by the action of centrifugal force. The upper side of the pocket is formed by wall 184, while the rear side is provided by downwardly-slanted wall 186, so that ink or dye thrown against this wall will move downwardly to flow outwardly through vent pipes 188 which return the dye or ink to the outer annular pockets 82, 84 and 86 and thereby recirculates the ink or dye from each wheel in its own system which is in excess of the amount required by the wheels for actual marking of the strand S. The ink or dye supply mechanisms will now be described.

Referring to Fig. 3, which illustrates wheel 169 aligned with its sump 112 on the base 64 brought about by rotating turn table 72 to show the relation of tubes in the recirculating system, it will be noted that the lower periphery of the wheel 169 is engaged to rotate in a slot 190 positioned in the upper end of a generally vertically-disposed tube 192, fitted into cooperating bores in the floor 194 of the member 169 and in the turn table 72 to cooperate with the innermost annular ink pocket 80. When the turn table 72 is rotated about the axis of the strand S, the tube is moved in a circular orbit, centering in the pocket 80. The lower face 196 of the tube 192 is cut off obliquely as is best seen in Fig. 10, so that it forms a scoop to pick up ink or dye in the pocket 80, to force it upwardly to flow through the slot 190 to contact the periphery of the marking wheel 169. Surplus ink or dye is removed from the wheel by a doctor blade 198 which wipes both sides of the wheel to collect the surplus ink whereby the action of centrifugal force is active to throw the dye outwardly against the oblique rearward wall 186 of the housing to flow out through the tube 188 to be recirculated in the system already described. The doctor blade 198 is attached to the front side of the member 169 in any convenient manner as by a rivet, a retainer wall 200 being provided to retain any surplus ink in the pocket 183 above the level of the pipe 188. The ink or dye is retained on the serrated periphery of the wheel 169 and is carried thereby to the strand S to form a spiral mark thereon as shown in Fig. 3A, as the rotation of the unit occurs about it. Fig. 4 illustrates the ink supply system of the same wheel 169 as shown in Fig. 3.

Referring to Fig. 5, a second tube 202 is provided for the marking disc 152, as shown in Fig. 11, being provided with a deeper slot 204 on its upper end, to cooperate with the periphery of the disc. The tube 202 is also positioned in cooperating bores in the floor of the member 169 which houses it and the turn table 72 but is juxtaposed radially outwardly to engage the central ink pocket 78 in the member 64. As shown in the drawing, a scoop 205 is provided at its bottom end. A drain tube 206 extends outwardly to engage the central outer pocket 84 to recirculate the surplus ink. In other respects the device is the same as the one described with reference to Figs. 3 and 4.

Referring to Fig. 6, a third tube 208 is provided to cooperate with the marking wheel 162 shown in Fig. 12. Here a slot 210 is provided in the forward wall of the tube with the upper end of the tube open to allow escape of surplus ink flowing up the tube by the action of the scoop 212 during rotation in the outer ink pocket 76. The back side of the marking wheel 162 cooperates with the slot to supply ink to its perimeter, the tube 208 being mounted farther outwardly in a radial direction in cooperating bores in the floor of the housing and the turn table to be rotatable in the locus of the ink pocket 76. The drain tube 214 extends outwardly to engage in the outer return pocket 82, as shown, to recirculate surplus ink in the same manner as before. In other respects, the device is the same as the other two already described with reference to Figs. 4 and 5.

Referring again to Fig. 2, the three wheels are juxtaposed about the strand S to contact the strand in about the same zone where all the marking occurs, all being positioned on the skew, so that several continuous spiral markings are formed on the surface of the strand as it

moves through this zone. The turn table 72 mounting the marking wheels rotates about the strand as the strand moves upwardly, and ink is scooped up by the lower ends of the tubes 192, 202 and 208, by the scoop-like lower openings 196, 205 and 212, to force the ink upwardly to impinge against the periphery of each of the marking wheels. Some turbulence occurs in the pockets 76, 78 and 80 and to prevent flow and mixing of ink or dye therebetween, annular depending skirts 214 on the turn table 72 are provided adjacent the adjoining wall between the pockets. As surplus ink is removed from the wheels by the doctor blades 198, it is thrown outwardly by centrifugal force and recirculated through the interconnecting ducts of various systems serving each wheel.

15 To protect the mechanism from dust and interference, a stationary cap 216 is provided for the ink-retaining base member to cover the wheels and the rotating turn table 72. A central hole 218 is provided, through which the upwardly-moving strand S passes to the heater which dries the ink. Thereafter the strand is pulled to the storage spool as already described.

It is to be understood that the above detailed description of the present invention is intended to disclose an embodiment thereof to those skilled in the art, but that 25 the invention is not to be construed as limited in its application to the details of construction and arrangement of parts illustrated in the accompanying drawings, since the invention is capable of being practiced and carried out in various ways without departing from the spirit of the invention. The language used in the specification relating 30 to the operation and function of the elements of the invention is employed for purposes of description and not of limitation, and it is not intended to limit the scope of the following claims beyond the requirements of the prior art.

35 What is claimed:

1. In a device of the class described, means to move 40 an elongated substantially cylindrical object through a zone to contact the periphery of rotatably mounted wheels whose axes are on the skew to apply ink in spiral paths to the surface of the object, a plate rotatably mounting the wheels adapted to rotate about the object in a transverse plane in timed relation thereto, a stationary ink storage member having ink retaining pockets therein, there 45 being a pocket for each wheel, ink-conveying means including a scoop cooperating with each wheel and its corresponding ink pocket to carry ink from the pocket and apply it to the periphery of the wheels as they are being rotated about the object so that the ink is applied to the 50 surface of the object by the wheels as they are rotated by the peripheral contactual relation between the object and the wheels.

2. In a device of the class described, means to move an 55 elongated substantially cylindrical object through a zone to contact the periphery of a rotatably mounted wheel whose axis is on the skew to apply ink in a spiral path to the surface of the object, a plate rotatably mounting the wheel adapted to rotate about the object in a transverse plane in timed relation thereto, a stationary ink storage member positioned below the plate having an annular ink-retaining pocket therein, ink-conveying means mounted in the plate cooperating with the wheel and its ink pocket to apply ink to the periphery of the wheel as it is being rotated about the object so that the ink is applied to the surface of the object by the wheel as it is rotated by the peripheral contactual relation between the object and the wheel.

3. In a device of the class described, means to move an 60 elongated substantially cylindrical object through a zone to contact the periphery of a rotatably mounted wheel whose axis is on the skew to apply ink in a spiral path to the surface of the object, a plate rotatably mounting the wheel adapted to rotate about the object in a transverse plane in timed relation thereto, a stationary ink storage member mounted below the plate having an annular

ink-retaining pocket therein concentric with the longitudinal axis of the object, tubular ink-conveying means depending from the plate cooperating with the wheel at its upper end and with the ink pocket at its lower end, having its opening exposed in the direction of rotation to pick up ink and apply it to the periphery of the wheel as the assembly is being rotated about the object, so that the ink is applied to the surface of the object by the periphery of the wheel as it is rotated by the peripheral contactual relation between the object and the wheel.

4. In a device of the class described, means to move an elongated substantially cylindrical object through a zone to contact the periphery of rotatably mounted wheels whose axes are on the skew to apply ink in several spiral paths to the surface of the object, a plate rotatably mounting the wheels adapted to rotate about the object in a transverse plane in timed relation thereto, a stationary ink storage member having annular concentric ink-retaining pockets in its upper surface, there being a pocket for each wheel, tube-like ink-conveying means positioned in substantially vertical position in the plate cooperating at their upper ends with each wheel and at their lower ends with the corresponding ink pocket to scoop up ink therefrom and to apply ink to the periphery of the wheels as they are being rotated about the object so that the ink is applied to the surface of the object by the wheels as they are rotated by the peripheral contactual relation between the object and the wheels.

5. In a device of the class described, means to move an elongated substantially cylindrical object through a zone to contact the periphery of rotatably mounted wheels whose axes are on the skew to apply ink in spiral paths to the surface of the object, a plate rotatably mounting the wheels adapted to rotate about the object in a transverse plane in timed relation thereto, a stationary ink storage member having open ink-retaining pockets in its upper surface concentric with the axis of rotation of the plate, there being a pocket for each wheel, tubular ink-conveying means including a scoop at its lower end to cooperate with the wheels and the corresponding ink pockets to carry ink upwardly to apply it to the periphery of the wheels as they are being rotated about the object so that the ink is applied to the surface of the object by the wheels in separated spirals as they are rotated by the peripheral contactual relation between the object and the wheels.

6. In a device of the class described, means to move an elongated substantially cylindrical object through a zone to contact the periphery of a rotatably mounted wheel whose axis is on the skew to apply ink in a spiral path to the surface of the object, a plate rotatably mounting the wheel adapted to rotate about the object in a transverse plane in timed relation thereto, a stationary ink storage member mounted below the plate having a pair of annular ink-retaining pockets therein connected together and concentric with the longitudinal axis of the

object, tubular ink-conveying means depending from the plate cooperating with the wheel at its upper end and with the inner ink pocket portion by means of a scoop at its lower end to pick up ink and apply it to the periphery of the wheel as the assembly is being rotated about the object, catch means including a depending pipe extending into the outer ink pocket portion to recirculate surplus ink, and means to supply ink to the pockets and control the level of ink therein.

7. In a device of the class described, means to move an elongated substantially cylindrical object through a zone to contact the periphery of a rotatably mounted wheel to be driven thereby and whose axis is on the skew to apply ink in a spiral path to the surface of the object, a plate rotatably mounting the wheel adapted to rotate about the object in a transverse plane in timed relation thereto, a stationary ink storage member mounted below the plate having an inner and an outer annular ink-retaining pocket therein being interconnected and concentric with the longitudinal axis of the object, tubular ink-conveying means depending from the plate cooperating with the wheel at its upper end by a slotted opening and with the ink pocket at its lower end by means of a scoop to pick up ink and apply it to a portion of the periphery of the wheel as the assembly is being rotated about the object, ink-catching means cooperating with the wheel including a depending pipe cooperating with the outer ink pocket to recirculate excess ink to the pockets, an ink supply to add ink to the pockets at a controllable rate and means to maintain the level of the ink in the pockets at a predetermined point.

8. In a device of the class described, means to move an insulated strand of substantially cylindrical cross-section through a zone to contact the serrated periphery of a rotatably mounted wheel to drive the same and whose axis is on the skew to apply ink in a spiral path to the surface of the strand, a horizontal plate mounting the wheel adapted to rotate about the strand in a horizontal plane in timed relation thereto, a stationary ink storage member mounted below the plate having an annular ink retaining pocket in its upper surface concentric with the longitudinal axis of rotation of the plate, tubular ink-conveying means depending from the plate cooperating with the wheel at its upper end by means of a slot and with the ink pocket at its lower end by a scoop which during relative rotation picks up ink and applies it to a portion of the periphery of the wheel adjacent the slot as the assembly is being rotated about the strand, means to catch surplus ink thrown from the wheel by centrifugal force and return it to the pocket, and means to supply and control the level of the ink in the pocket.
